B. A. SMITH

BLOTTER HOLDER

Filed Oct. 1, 1925

INVENTOR.

Bryce A. Smith

UNITED STATES PATENT OFFICE.

BRYCE A. SMITH, OF GLENDALE, CALIFORNIA.

BLOTTER HOLDER.

Application filed October 1, 1925. Serial No. 59,904.

My invention relates to blotter holders and has for its principal object the provision of a mechanical device which will serve as a blotter holder and which is 5 adapted for operation to move the blotter into contiguity with a surface to be blotted.

Another object is the provision of a device of the above character, adapted to hold a commonly used ink blotter in a position plainly visible and segregated from 10 papers and the like usually found on a desk where a blotter is used.

Another object of the invention is to provide a simple and stable device for carrying 15 out the above objects, while being always convenient and readily discernible among other objects, papers and the like.

Still other objects and advantages of my 20 invention will appear hereinafter and will be better understood because of the order in which they occur.

I have illustrated my invention by the accompanying drawings in which:

Figure 1 is a view in side elevation of one 25 embodiment of my invention.

Figure 2 is a side view thereof, partly in section, showing the device in the operated position.

Figure 3 is a front elevation with blotter 30 in its normal position.

Figure 4 is a plan view with blotter removed.

In carrying out my invention I provide a base 5 of any suitable material, which supports a rod 6 and the lug 7. Coiled around 35 the rod 6 is the compression spring 8 above which and slidably mounted on the rod is the handle 9 at the upper end of which and attached thereto is the knob 10. The clasp 11 is pivotally connected to the lug 7 at 40 12 and a connecting link 13 is pivotally connected to the handle 9 and the clasp 11 at 14 and 15 respectively. The clasp 11 is 45 preferably made of spring material so that it will firmly grip a blotter or the like after the same has been inserted.

It will be apparent now that when a blotter 16 is inserted in the clasp 11, by 50 pressing on the knob 10 the spring 8 will be compressed and through the connecting link 13 the clasp 11 and the blotter 16 will

take the position shown by Figure 2, the blotter 16 being disposed contiguously with the surface 17 upon which the base 5 rests. Upon releasing the pressure on the knob 10, 55 the spring 8 will expand and automatically restore the parts to their normal position as shown in Figures 1 and 3.

The entire device is portable and is adapted to be located in any convenient 60 position on a desk or the like.

In using the device it is picked up by grasping the knob 10 on the upper end of the handle, and then depositing the device with the base adjacent to the area which 65 is to be blotted. The handle is then depressed, moving the blotter as described into contiguity with the surface to be blotted.

Having described my invention, what I 70 claim is:

1. In a blotter holder, a portable horizontal base, a vertical guide immovably fixed to said base, a push rod slidable vertically on said guide, a clip pivoted to said base 75 to move to a position adjacent an outer edge of said base and a rigid link pivotally connected at one end to said push rod and pivotally connected at the other end to said clip. 80

2. In a blotter holder, a portable horizontal base; a vertical guide immovably fixed to said base, a push rod slidable vertically on said guide, a clip pivoted to said base to move to a position adjacent an outer edge 85 of said base and a rigid link pivotally connected at one end to said push rod and pivotally connected at the other end to said clip, a compression spring disposed around said guide between said base and said push rod constantly urging said push rod upwardly on said guide; said spring and link co-acting to normally hold said clip angularly disposed relative to said base; whereby depression of said push rod will act to 90 dispose said clip into substantially horizontal position, said clip having a blotter receiving end normally disposed vertically of the base; whereby such depression of said push rod will act to move the blotter holding end downwardly and outwardly away 95 from said base. 100

3. In a blotter holder, a horizontal base, a fixed guide stem rising vertically from said base, a tubular push rod telescopically fitted over said guide stem, a compression spring surrounding said stem between said base and said push rod, a U-shaped blotter holding clip pivoted at its closed end adja-

cent an outer edge of said base with an open blotter receiving end vertically disposed with regard to said base and a link 10 pivotally connected at one end to said clip and at the other end to said push rod.

In testimony whereof I affix my signature.
BRYCE A. SMITH.
